(57) **CLAIM**

The ornamental design for a display screen with animated graphical user interface, as shown and described.

DESCRIPTION

1. Display screen with animated graphical user interface

1.1 : Front view 1

1.2 : Front view 2

1.3 : Front view 3

1.4 : Front view 4

The broken lines depict portions of the display screen with animated graphical user interface that form no part of the claimed design; the dash-dot broken lines define the bounds of the claimed design and form no part thereof. The appearance of the transitional image sequentially transitions between the images shown in reproductions 1.1-1.4. The process or period in which one image transitions to another image forms no part of the claimed design.

1 Claim, 4 Drawing Sheets
